(57) **CLAIM**

The ornamental design for a terminal for authentication as shown and described.

DESCRIPTION

FIG. 1 is an enlarged-scale front, left side, top perspective view of a terminal for authentication showing our new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof; and,

FIG. 7 is a bottom plan view thereof.

The dashed broken lines in the figures depict portions of the terminal for authentication that form no part of the claimed design. The long and short dashed lines depict a boundary of the claimed design and form no part thereof.

1 Claim, 7 Drawing Sheets
